UNITED STATES PATENT OFFICE.

DUDLEY T. FISHER, OF COLUMBUS, OHIO, ASSIGNOR, BY MESNE ASSIGNMENTS, TO THE JEFFREY MANUFACTURING COMPANY, A CORPORATION OF OHIO.

CABLE-REEL FOR HAULAGE MECHANISM.

1,113,974.

Specification of Letters Patent.

Patented Oct. 20, 1914.

Application filed September 25, 1907, Serial No. 394,508. Renewed November 8, 1911. Serial No. 659,245.

To all whom it may concern:

Be it known that I, DUDLEY T. FISHER, a citizen of the United States, residing at Columbus, in the county of Franklin and State of Ohio, have invented certain new and useful Improvements in Cable-Reels for Haulage Mechanism, of which the following is a specification, reference being had therein to the accompanying drawing.

10 This invention relates to improvements in draft or haulage mechanism for electric locomotives of the sort employed for pulling from one point to another cars which are not provided with their own engines or motors. For example, in coal mines relatively small cars are used which, while being loaded are separated from each other and scattered over more or less of the mine, one in one room or at one loading point and others at others. The older plan, where animal power was used, was to haul each of these cars singly by an animal from the room, after it had been loaded, to a collecting point where a number of the cars were coupled together to form a train or "trip." Since the introduction of electric power use has been made for this purpose of "gathering" locomotives, each having a reel with an electric cable thereon, the terminal of which 25 can be connected electrically to a current-supplying wire, so that as the car moves away from the source of supply, the cable on the reel will maintain a continuity of electric conductors to the motor. In using this 30 apparatus, the locomotive is itself run into the rooms successively and coupled to the isolated loaded cars and thereafter hauls these to the gathering point. Under many circumstances these gathering locomotives 35 with cable reels cannot be used to advantage, particularly where the mine roof is low or where the track has been hastily constructed, as the branch tracks frequently are which extend from the entry into the room. 40 The present invention relates to an apparatus adapted to be attached to an ordinary locomotive and of such nature that the locomotive can remain in the entry or at some distant point and yet the loaded car can be 45 hauled by power toward it while it remains stationary.

The object of the invention is to provide improved structural features and an improved arrangement of parts.

50 A further object is to provide improved

means for controlling the operation of the reel.

Figure 1 is a top plan view of a mining locomotive embodying my improvements, some of the parts being indicated conventionally. Fig. 2 is a side elevation of the same. Fig. 3 is a view showing the reel and its power transmitting devices, in vertical central section and showing an electric motor partly in outline and partly in section. Fig. 4 is a side elevation of the motor and reel. Fig. 5 is a horizontal section on the line $x-x$, Fig. 3.

A indicates a car, an electric locomotive of the kind used in coal mines being selected for the purpose of illustration. Its wheels B are fitted to the track rails. Its body is formed of a heavy cast frame having the side parts C, C and the end connecting parts D, D. Many of the parts of the car or locomotive are indicated conventionally by dotted lines. At E the electric motor is situated in the space between the two axles b, b'. This motor is geared to one of the axles in any suitable way, and by preference the axles are geared together or connected by chains and sprockets. At F there is a chamber or space left for the motorman and for the parts which he is called upon to manipulate frequently, such as the wheel of the controller at G and the hand wheel of the brake mechanism at H.

At the end of the locomotive opposite to that where the motorman is placed I arrange a reel for the haulage cable. This is indicated by 1 and is mounted on a vertically arranged shaft 2. This shaft is secured to a base 3 which is in the form of a strong bar extending across from one of the side elements C of the car body to the other, and firmly bolted thereto. The shaft 2 is fastened by a key 4 to this base in such a way that it is held firmly against rotation. The reel 1 can rotate loosely and freely around this shaft when it is disengaged from the other parts. The reel has an anti-friction lining 5 between it and the shaft 2, this resting upon the base 3.

16 indicates a hub-like part for the reel to give it an extended bearing. To this hub or sleeve is secured, or with it is formed a gear wheel 9.

11 is a spur gear wheel mounted loosely on the shaft 2 above the reel hub. This gear wheel 11 is of a slightly larger diam- 110

- ter than the wheel 9, and has one more tooth, for a purpose to be described. With this wheel are combined devices for locking it to the shaft 2 and holding it stationary.
- 5 To accomplish this the wheel itself may be provided with a clutch-element, preferably by forming jaws or teeth 24 upon its upper side. With this clutch-element a movable element such as a pin or cross-bar 18 can engage, it extending through slots 19 in the shaft 2 and being movable into and out of engagement with the jaws or teeth 24. To so move it, use is made of the rod 21 connected to the clutch pin 18 and extending downward through the shaft 2. At the lower end the rod is connected to a bell-lever 22 from which there extends an operating rod 23 to the motorman's end of the car.
- 10 The shaft 2, at its upper end, supports the field frame 25 of the motor 8. The armature 26 is supported by the collar 6 on the shaft 2 and revolves freely on suitable anti-friction bearings.
- 15 15 is a sleeve or cylinder secured to the under-side of the armature and extending downward therefrom. From the cylinder there extend still farther downward arms 27, which, at their lower ends carry a ring 28 concentric with the shaft 2. This ring is formed with a number of bearings 29 and in each of these is mounted a shaft 12. Each shaft 12 carries two pinions 13 and 14. These pinions differ slightly in size, the upper one having the smaller diameter, but have the same number of teeth. The pinions 13 mesh with the wheel 11, and those at 14 mesh with the wheel 9. When the armature is revolved the pinion shafts 12 are rotated bodily around the shaft 2 and if the wheel 11 is stationary, that is, locked to the shaft 2, it will be seen that rotary motion will be transmitted from the armature to the reel and that the speed of the latter will be greatly reduced relative to that of the former.
- 20 The gear chamber inside of the cylindrical part of the reel is closed at the top by the flange 30 on the cylinder 15, and by the cover plate 31 secured to the top of the reel. This chamber can be filled with oil and perfect lubrication of the relatively moving surfaces can be effected. The haulage cable 32 may be taken off from the reel 1 at any angle but I prefer to pass it over vertical and horizontal guide rollers 33, 34 and thence to the opposite end of the locomotive where I provide guide sheaves, 35, 36, which permit said cable to be taken off for draft purposes at a great variety of angles.
- 25 The manner of using an apparatus of the kind above described will be readily understood. The locomotive is stopped in the mine entry in such position that the motorman can look through the passage-way of the

"mouth" into the room. His assistant, the "trip-rider", takes the end of the cable and carries it into the room and couples it to the car to be drawn out. The motorman first by the draw-rod 23 and the rod 21 disengages the clutch-pin 18 from clutch-jaws 24 allowing the reel to freely rotate. After the end of the cable is coupled to the car the motorman can, by means of the rod 23 and the rod 21, thrust the clutch pin 18 into engagement with the gear wheel 11. He then starts the motor 8 and the reel is caused to wind up the cable and draw the car from the room to the track in the entry. When a loaded car is sufficiently close to the locomotive the latter is set in motion by means of its motor E and the loaded car is drawn to the point where the trains or "trips" of several cars are made up.

I do not herein claim the arrangement of the motor, the reel and the cable guide devices with respect to the locomotive as a whole as these features are presented and claimed in my co-pending application for locomotives with haulage cable mechanisms, Serial No. 393,829, filed September 20, 1907.

What I claim is:

1. The combination of a shaft, a reel rotatable about the shaft and provided with a central chamber containing the shaft, a gear wheel in the said chamber connected to the reel and rotatable therewith, a second gear of different diameter from the first mounted stationarily within the chamber co-axially with the first gear, a shaft parallel to the reel axis and revoluble bodily around it, gear wheels on the said parallel shaft meshing respectively with the two aforesaid gear wheels, a support and driver for the shaft located partly within the chamber and extending axially to a point outside thereof, and means for applying power to the said support and driver to cause the bodily movement of the parallel shaft about the reel axis.

2. The combination with a cable reel and a vertically arranged stationary shaft about which it is rotatable, of a motor mounted on the shaft at the upper end thereof above the reel with its armature rotatable about the axis of the shaft, a stationary gear wheel mounted concentrically with the shaft, a rotary gear wheel mounted concentrically with the shaft and secured to the reel, the two said gear wheels having different diameters, and other gear wheels meshing with the aforesaid and connected together and with the armature for revolution therewith around the axis of the reel.

3. The combination with a vertically arranged stationary shaft, and a rotatable reel concentric with the shaft and having an enlarged central chamber having tight bottom and side walls for the retention of lubricant, of a motor mounted on the shaft at

the upper end thereof, and power transmitting and speed reducing gearing positioned in the lubricant chamber and carried in part by the motor armature.

5 4. The combination of a reel mounted on a vertical axis and having a relatively large central chamber, a motor above the reel having an armature with revolving projections extending downward into said chamber, and planetary gear wheels carried by the said revolving projections and serving to transmit power to the reel.

10 5. The combination with a vertically arranged shaft, and a reel mounted for rotation about the said shaft and having an enlarged central chamber having tight bottom and side walls for the retention of lubricant, of power transmitting and speed reducing gearing in the said lubricant chamber, means entering said chamber at the top for suspending some of the said gearing, and means for applying power to the gearing through the said suspending means.

15 6. A cable reeling mechanism comprising in combination a fixed hollow shaft, a reel rotatably mounted upon said shaft having an interior gear chamber, a motor mounted upon the shaft with one of its elements rotatable about the axis thereof, a reduction 20 gearing interposed between the said rotatable motor element and the reel and mounted within the said gear chamber about the said fixed shaft, a clutch mechanism for said reduction gearing at one end of the 25 reel, and an operating rod extending coaxially through the said reel and within the hollow shaft to the other end of the said reel and operating levers connected with said rod.

30 7. In a cable winding mechanism, the combination of a mast, a reel rotatable about the mast, a motor mounted on the mast above the reel and arranged with one of its elements rotatable about the axis thereof, and a power connection between the motor and the reel positioned with all of its 35 elements above the lower horizontal plane of the reel.

40 8. In a cable winding mechanism, the combination of a vertical mast, a reel rotatable about the axis of the mast and provided with an inner chamber concentric therewith, a motor mounted on the mast above the reel and arranged with one of its elements rotatable about the axis thereof, and power transmitting mechanism between the motor and the reel comprising gearing located within the chamber and capable of driving the reel at a speed different from that of the rotatable element of the motor.

45 9. In a cable winding mechanism, the combination of a reel mounted for rotation about a vertical axis and provided with a chamber concentric with the axis, a motor mounted above the reel with one of its ele-

50 ments rotatable about the reel axis, an annular gear frame positioned in the chamber and connected with the rotatable element of the motor, and gearing mounted on the said gear frame and serving to cause rotation of 70 the reel at a speed different from that of the gear frame and the rotatable motor element.

55 10. In a cable winding mechanism, the combination of a vertical non-rotatable mast, a reel rotatable about the mast and provided with a chamber concentric therewith, a gear wheel mounted in the chamber co-axially with the mast, means for securing the gear wheel to the mast to hold it 75 against rotation, a gear wheel secured to the reel within the chamber, connecting gearing in the chamber meshing with the two said gear wheels, and means for bodily moving the said connecting gearing to cause 80 85 the rotation of the reel.

60 11. In a cable winding mechanism, the combination of a vertical non-rotatable mast, a reel rotatable about the mast and provided with a chamber concentric therewith, a gear wheel mounted in the chamber co-axially with the mast, means for securing the gear wheel to the mast to hold it 90 against rotation, a gear wheel secured to the reel within the chamber, connecting gearing 95 in the chamber meshing with the two said gear wheels, a motor mounted on the upper end of the mast, and a connection between the motor and the connecting gearing, whereby the connecting gearing may be 100 moved to cause rotation of the reel.

65 12. In a cable winding mechanism, the combination of a vertical mast, a reel mounted for rotation about the mast, a gear wheel mounted co-axially with the mast, a manually controllable means for locking the gear wheel to the mast to prevent rotation, a gear wheel secured to the reel, connecting gearing meshing with the two said gear 105 wheels, and means for bodily moving the 110 connecting gearing to cause the rotation of the reel.

70 13. In a cable winding mechanism, the combination of a vertical mast, a reel mounted for rotation about the mast, a gear wheel mounted co-axially with the mast, a manually controllable means for locking the gear wheel to the mast to prevent rotation, a gear wheel secured to the reel, connecting gearing 115 meshing with the two said gear wheels, a 120 motor mounted on the upper end of the mast, and a connection between the motor and the connecting gearing, whereby the connecting gearing may be moved to cause rotation of the reel.

75 14. In a cable winding mechanism, the combination of a vertical hollow mast, a reel rotatable about the mast and provided with a chamber concentric with the mast, a gear wheel rotatably mounted on the mast 130

and provided with clutch teeth, a bar extending diametrically through the mast and adapted to engage with the said clutch teeth, a manually controllable means extending through the central opening of the mast and connected with the bar to move it into or out of engagement with the clutch teeth, a gear wheel secured to the reel, connecting gearing meshing with the two said gear wheels, and means for bodily moving the connecting gearing to cause rotation of the reel.

15. In a cable winding mechanism, the combination of a vertical hollow mast, a reel rotatable about the mast and provided with a chamber concentric with the mast, a gear wheel rotatably mounted on the mast and provided with clutch teeth, a bar extending diametrically through the mast and adapted to engage with the said clutch teeth, a manually controllable means extending through the central opening of the mast and connected with the bar to move it into or out of engagement with the clutch teeth, 20 a gear wheel secured to the reel, connecting gearing meshing with the two said gear wheels, a motor mounted on the upper end

of the mast, and a connection between the motor and the connecting gearing, whereby the connecting gearing may be moved to cause rotation of the reel.

16. In a cable winding mechanism, the combination of a vertical mast, a reel rotatable about the mast and provided with a chamber concentric therewith, a motor mounted on the mast and provided with an inner element rotatable about the mast, a cylindrical gear carrying frame secured to the inner rotatable element of the motor and extending downward into the said chamber, 35 gearing carried by the frame within the chamber and serving to drive the reel, an annular outward extending flange on the cylindrical gear carrying frame, and an annular inward extending flange at the top of 40 the chamber in the reel, the said inward extending flange overlapping the aforesaid outward extending flange.

In testimony whereof I affix my signature, in presence of two witnesses.

DUDLEY T. FISHER.
